UNITED STATES PATENT OFFICE.

STEPHEN M. SPRAGENS, OF CINCINNATI, OHIO.

CALENDAR.

Application filed March 1, 1922. Serial No. 540,815.

To all whom it may concern:

Be it known that I, STEPHEN M. SPRAGENS, a citizen of the United States, and a resident of Cincinnati, in the county of 5 Hamilton and State of Ohio, have invented certain new and useful Improvements in Calendars, of which the following is a full, clear, and exact description, reference being had to the accompanying drawings, 10 forming part of this specification.

My invention relates to calendars having suspension means and separate sheets or leaves for desired periods of time.

A considerable practice has sprung up 15 in recent years in art calendars, mainly used for advertising purposes, in which there are six sheets or pages bearing a monthly calendar on each side and some sort of mounting whereby each sheet as its use on one side is 20 completed is preserved intact with the calendar, so as to be used on its other side. In this way a monthly page calendar is provided with saving in bulk and in paper, and a very high type of color printing is possible without prohibitive cost.

The use of such calendars for advertising purposes tends to destroy their artistic merit, unless the advertisement of the donor appears in such a way as not to break the 30 continuity of the text of the calendar, or destroy the effect given by the artistic colored pictures.

It is the object of my invention herein, to provide a calendar of the desired number of 35 sheets formed in a thin pad, and to provide a support for the pad, that not only permits of a folding back out of sight of used pages, but provides an excellent, entirely separate element in connection with the pad support 40 for printing the advertisement or name of the donor of the calendar.

This object, as well as other incidental improvements to be noted, I accomplish by that certain construction and arrangement 45 of parts to be hereinafter more specifically pointed out and claimed.

In the drawings,

Figure 1 is a front elevation of a calendar made according to my invention. 50 Figure 2 is a vertical section taken through the calendar.

The calendar pad, as shown, is formed of six leaves 1, although the number of leaves is not essential. These leaves will each one

preferably serve as a monthly calendar and 55 the front leaf looking at one side of the calendar may be a cover, as shown in Figure 1, in which case I may provide seven leaves.

The essential point in the pad structure is that the leaves are secured together at 60 their upper ends by means of a binding strip 2, in this case metal. This metal strip embraces the upper edges of the leaves or pages, and also engages and holds the ends of a cord or cords 3.

A name or advertising card is provided, of the same width as the pad, as shown at 4, which card may have an aperture 5 for mounting the calendar on a hook or nail, or may have some other accepted means of 70 mounting the entire device on a wall or elsewhere.

The card is equipped, preferably, with a metal binding 6, similar to the binding of the pad, which binding also engages the 75 cord or cords 3.

The length of the cord between the end of the binding 2 and the binding 6 will be such as to permit the leaves of the calendar to be inserted through the space left between card 80 and pad, and folded back, so as to be preserved for use later on their hitherto unused sides.

The card will preferably have the donor's name or advertisement printed thereon, on 85 both sides, so that when the first six months have passed, the entire device can be turned about to expose the rear faces of the leaves.

This structure is much preferable over a mere mounting cord set in the upper edge 90 of the pad, since it provides a place for a separate advertisement, exposed, at all times that the calendar is used without defacing the leaves, and thus permitting the leaves to be printed alike for all users.

A cord also does not provide a rectangular space for folding back the leaves, as does the device above described, but instead provides a triangular space, which pulls at the edges of the leaves that are 100 turned back.

I have not intended by the showing in my drawings to prescribe a certain shape or size for my calendar, as obvious modifications are intended by me to be within the scope of my invention, which is not to be limited to any particular shape or number of leaves.

Having thus described my invention, what I claim as new and desire to secure by Letters Patent, is:—

A calendar comprising a pad of leaves, a metal binding strip adapted to confine the upper edges of said leaves, cord ends secured in the ends of said binding, a card separate from the pad, a metal binding strip

on the card, said binding being of substantially the same length as the pad binding strip, and engaging the cord at the ends so as to leave a rectangular space between the card and pad for a folding back of the leaves of said pad through said space. 10

STEPHEN M. SPRAGENS.
